UNITED STATES PATENT OFFICE.

WILLIAM J. NESBITT, OF LOS ANGELES, CALIFORNIA.

HEEL-CUTTING APPARATUS.

1,239,210.

Specification of Letters Patent.

Patented Sept. 4, 1917.

Application filed January 29, 1917. Serial No. 145,300.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable 10 others skilled in the art to which it appertains to make and use the same.

The invention relates to improvements in heel cutting apparatus, and it may be said to consist in the provision of the novel and 15 advantageous features and in the novel and improved construction, arrangement, and combination of parts and devices as will be apparent from the description and claims which follow hereinafter.

20 The main object of the invention is to provide a novel and improved heel cutting apparatus in which the circular saw is mounted on a pivoted arm and slideable on said arm so that it can be adjusted transversely to the 25 heel clamping device.

Another object of the invention is to provide a novel and improved heel cutting apparatus which can be easily and quickly attached to or detached from the frame which 30 carries other devices in use for repair work on boots or shoes.

Further objects of the invention are to provide a heel cutting apparatus of the character specified which is simple and compact, 35 economical to manufacture, install, and use, easy and convenient to operate, and effective in action.

Other objects and the advantages of the invention will be apparent to those skilled 40 in the art from a careful consideration of the following description of the preferred construction embodying the invention, taken in connection with the accompanying drawings in which

45 Figure 1 is a broken front elevational view showing the heel cutting apparatus mounted on the frame; Fig. 2 is a broken sectional view taken on the line 2—2 of Fig. 1 and showing the heel cutting apparatus in side 50 elevation; Fig. 3 is a broken plan view showing the heel cutting apparatus; and Fig. 4

is a sectional view of a portion of the apparatus taken on the line 4—4 of Fig. 3.

The frame 10 may be of the usual or any approved construction, and it has suitably 55 arranged thereon the shaft 11 on which may be mounted the burnishing device indicated at 12, and also other devices, not shown, adapted to be used for doing repair work on boots and shoes. On the spaced bars 13 and 14 of the frame 10 are mounted the spaced supports 15 and 16 which are easily and quickly attached to or detached from the hollow bars 13 and 14 by having their ends provided with split sleeves whose parts 17 65 and 18 are clamped on said bars by the bolts 19 which connect the parts 17 and 18.

The heel clamping device may be of any approved construction, that shown consisting of the coacting heel gripping jaws 20 70 and 21 which are carried by an adjustable mounting on the support 16. The adjustable mounting preferably consists of the split socket 22 which has its parts connected by the bolts 23 and is fitted on a ball 24 75 which is provided with a stem 25 suitably secured to the support 16. The jaw 20 is attached to the socket 22 and is provided with an extension 26 having a guideway 27 in which is slidably fitted the extension 28 80 which is provided on the jaw 21. On the jaw 20 is a lug 29 which has thereon the pivot 30 on which is mounted the sector 31 provided with teeth 32 in mesh with teeth 33 on the extension 28. The sector is provided with an arm 34 having thereon the handle 35. The arm 34 has thereon the pivot 36 on which is mounted the dog 37 which is adapted to engage teeth 38 on the lug 29 to lock the sector 31 after the latter has 90 been moved by the handle 35 to adjust the movable jaw 21. The dog 37 may be disengaged from the teeth 38 by pressing up on the lever 39 which is pivotally mounted on the arm 34 adjacent to the handle 35 and is 95 connected by the link 40 to the dog 37. A spring 41 is arranged between the handle 35 and the lever 39 to normally press against the latter so that the dog 37 is moved to engagement with the teeth 38. The mounting 100 for the heel clamping device is locked in adjusted position by turning the screw

42 which is mounted on the socket 22 and has a pointed end adapted to engage the ball 24 when said screw 42 is turned.

A shaft 43 is mounted on the standards 44 and 45 which are suitably secured on the supports 15 and 16. Against the collar 46 on the shaft 43 is pivotally mounted one end of the arm 47 which latter has on its other end the spaced bearings 48 and 49 in 10 which journals the shaft 50 on which is mounted the circular saw or cutter 51. Between the bearings 48 and 49 is arranged the sprocket wheel 52 which is provided with a key 53 which is slidably fitted in the longitudinal groove 54 in the shaft 50 so that the sprocket wheel 52 is feathered on the shaft 50. The arm 47 is provided with a lateral extension 55 which has thereon the pivot 56 to which is connected one end of the lever 20 57 which has its other end provided with the handle 58. Between collars 59 and 60 on the shaft 50 is arranged the sleeve 61 which is provided with pins 62 fitted in the slots 63 which are provided in the curved portion 64 of the lever 57 and in the curved strip 65 which is attached to the lever 57 by the bolts 66. A lever 67 is mounted on the pivot 68 which is arranged on the lever 57 adjacent to the handle 58, and said lever 67 is connected by the link 69 to the dog 70 which is slidably mounted on the lugs 71 and 72 which are provided on the strip 65 and on the lever 57. A spring 73 arranged between the handle 58 and the lever 67 normally 30 presses against the lever 67 to have the dog 70 engage the teeth 74 on the extension 55 so that the lever 57 can be locked in adjusted position. A spring arm 75 is attached to the collar 46 and bears against the underside of the arm 47 and normally holds the arm 47 in raised position. The upward movement of the arm 47 is limited by the stop 76 which is attached to the collar 46. The shaft 50 may be driven by any suitable means, that shown consisting of the 40 sprocket chain 77 which is connected to the sprocket wheel 52 and to the sprocket pinion 78 which latter is secured to the sleeve 79 which is arranged between the arm 47 and the collar 80 on the shaft 43. An electric motor 81 has on its shaft 82 a sprocket pinion 83 which is connected by the sprocket chain 84 to the sprocket wheel 85 which is secured to the sleeve 79. The motor 81 may 50 be suitably mounted on the support 16, and the shaft 11 may be mounted in a bearing 86 which is provided on the standard 44. The shaft 11 may be operatively connected to the sleeve 79 by the spur wheel 87 which is secured to the shaft 11 and arranged in mesh with the spur wheel 88 which latter is secured to the sleeve 79.

From the foregoing the construction, mode of operation, and the advantages of the heel

cutting apparatus will be understood by those skilled in the art. It will be evident that the shoe 89 can be placed between the jaws 20 and 21 and clamped by moving down and locking the jaw 21, see Fig. 2, and the mounting of the heel clamping device permits of disposing the heel 90 at any desired angle to the cutter 51. By swinging the lever 57 the shaft 50 can be moved to adjust the cutter 51 transversely toward or away from the heel clamping device so that the desired amount of the heel 90 can be cut off when the arm 47 is moved down by the lever 57 to have the cutter 51 cut the heel 90.

The construction which has been particularly illustrated and described admits of changes and modifications, wherefore the right is reserved to all such changes and modifications as do not depart from the spirit and scope of the invention, which is defined in the appended claims.

I claim:

1. In heel cutting apparatus, the combination of an adjustable heel clamping device, a pivotally mounted arm, a shaft slidably mounted on said arm, a saw on said shaft, and means including a sprocket wheel feathered on said shaft to drive the shaft.

2. In heel cutting apparatus, the combination of a heel clamping device, a pivotally mounted arm, a saw, a shaft on which the saw is mounted, and means whereby said shaft is slidably mounted on the arm so that the saw can be adjusted transversely toward or away from the heel clamping device.

3. In heel cutting apparatus, the combination of a heel clamping device, a pivotally mounted arm, a spring arm arranged to normally support the first mentioned arm, a saw, and a shaft for the saw journaled adjustably on the first mentioned arm so that the saw can be adjusted transversely toward or away from the heel clamping device.

4. In heel cutting apparatus, the combination of a shaft, an arm pivotally mounted on said shaft, a saw, a shaft slidably mounted on said arm and having said saw mounted thereon, a sprocket wheel feathered on the last mentioned shaft, and suitable means to operate the sprocket wheel.

5. In heel cutting apparatus, the combination of a pivotally mounted arm, a saw, a shaft slidably mounted on said arm and having the saw mounted thereon, a sprocket wheel feathered on the shaft, a stop adapted to limit the upward movement of said arm, and a spring arm arranged to normally support the first mentioned arm and move it to raised position.

6. In heel cutting apparatus, the combination of an adjustable heel clamping device, a shaft, an arm pivotally mounted on said shaft, a circular saw, a shaft for the saw

slidably mounted on said arm so that the saw can be adjusted transversely toward or away from the heel clamping device, a sprocket wheel feathered on the last mentioned shaft, suitable means to operate the sprocket wheel, a stop adapted to limit the upward movement of said arm, and a spring arm arranged to normally support the first

mentioned arm and move it to raised position.

10

In testimony whereof, I have signed my name to this specification at Los Angeles, county of Los Angeles, State of California, this 19th day of January A. D. 1917.

WILLIAM J. NESBITT.
